UNITED STATES PATENT OFFICE.

HARRY A. JOHNSTON, OF SAN FRANCISCO, CALIFORNIA, ASSIGNOR TO
HERCULES GAS ENGINE WORKS, A CORPORATION OF CALIFORNIA.

SPARKING IGNITER FOR GAS-ENGINES.

No. 836,503.

Specification of Letters Patent.

Patented Nov. 20, 1906.

Application filed March 8, 1905. Serial No. 249,036.

To all whom it may concern:

Be it known that I, HARRY A. JOHNSTON, a citizen of the United States, residing at San Francisco, in the county of San Francisco and State of California, have invented certain new and useful Improvements in Sparking Igniters for Gas-Engines, of which the following is a specification.

My invention relates to gas and vapor engines, and more particularly to electrical igniters or sparking devices for such engines.

The object of my invention is to provide a sparking device which will not only be efficient in operation, but reliable, and which will not be subject to intermissions and failures in operation.

Another object is to provide a more simple construction with fewer parts and to increase the efficiency of the device by such simplifying of the construction and such reduction of parts.

Generally speaking, an embodiment of my invention shows a stationary and a movable electrode and means for controlling the movable electrode comprising a movable stop which normally keeps the electrodes out of contact and a single spring connected both to said stop and to said electrode and exerting its force upon both. Means are provided for moving the stop temporarily and against the force of the spring, so that such spring can act upon the movable electrode and close the circuit, while the return of said stop to its normal position causes the circuit to be broken sharply and positively, producing the spark. Such an embodiment of my invention is shown in the accompanying drawings, in which—

Figure 1 is a top plan showing the supporting and operating parts of the igniter outside the engine-cylinder. Fig. 2 is an elevation of the end of the cylinder, broken away to show the parts related to the igniter in section. Fig. 3 is a bottom plan of the casting which supports the igniter members. Fig. 4 is a perspective view of the arm by which the oscillating electrode is controlled. Fig. 5 is an elevation of the igniter-casting looking from the top of the sheet toward Fig. 1.

In the drawings, 1 represents a gas-engine cylinder of either horizontal or vertical type, and 2 is a supporting-plate bolted upon the outside thereof. This plate has an opening in line with an opening in the cylinder, as

shown in Fig. 2, and is provided with a raised rim 3, which surrounds said opening and forms a seat for the igniter-casting 4. It is evident, however, that the said casting can be secured directly to the cylinder and the plate 2 omitted. The casting 4 has projecting hooked lugs 5, through which bolts 6 pass into the cylinder-head and are secured by nuts 7. After loosening these nuts, the casting, with all the parts carried by it, can be removed bodily and replaced without taking off the nuts or detaching the bolts. The casting is bored through to receive the pin 8, which is insulated from said casting, as shown in Fig. 2, and the lower end of which projects into the opening in the cylinder. This pin is held stationary by a nut at its outer end and is adapted to be connected to one of the wires from a suitable generator. At its lower end it carries an electrode 9, preferably of platinum and having a flat end. An oscillating-pin 11 is mounted in a bore of the casting, which bore is formed in a projection 10, extending into the cylinder. The lower end of pin 11 is slotted to receive and hold the arm 12, carrying the terminal electrode 13, which is similar to the electrode 9 and is adapted to meet it squarely, so that the two flat faces can come into contact throughout their area. On the upper end of the pin 11 is secured a projecting arm 14. An oscillating pin 15 is movable in a bore of the casting and carries an arm 16, having a flat face which normally bears against a corresponding surface of the arm 14, as clearly shown in Fig. 1. The upper end of pin 15 is threaded and carries a milled washer 17, to which is connected one end of a spring 18, coiled upon the pin and having its other end connected to the arm 14.

The washer 17 is a tension-regulator for the spring and is held at any adjustment for tension by a nut 19. The arm 16 has a projection 21, which is rounded on its under side, as shown in Figs. 4 and 5. This projection is struck at proper intervals by a cam 22, shown as carried by a disk 23 on the rotary shaft 24. The said disk has its face always in contact with the projection, so as to limit the movement thereof. This shaft is driven, through suitable gearing, by a shaft 25, which is connected in any desired manner to the engine-shaft or any part operated by the latter, so as to revolve and cause the cam-

disk to revolve at the proper relative speed to time the ignition.

The single spring 18 performs a double function, which in igniters of this class have been performed by two separate springs which tend to neutralize each other, and hence deprive the igniter of that sharp positive action which is so necessary for regular and successful sparking. The spring 18 is not only connected with oscillating pin 15, but also with the oscillating electrode-pin 11, and both pins are always under tension. The normal tension pulls the arms 14 and 16 together and separates the electrodes, as shown in the drawings. The tension upon arm 14 always tends to move the pin 11 and would do so did not arm 16, upon which pressure is opposite, act as a direct stop. When the cam acts upon arm 16, the latter is moved away from arm 14 and permits the spring to exert its tension upon said arm and bring the movable electrode into momentary contact with the fixed electrode. Arm 16 having the pressure of the whole coil upon it snaps back as soon as the cam has passed, strikes and forces back arm 14, and breaks the contact, which produces the spark. Thus the single spring performs two separate functions without any tendency toward a neutralization of its power at any time, for, first, its normal tension keeps the arms 14 and 16 in contact and the electrodes apart, and, secondly, owing to the connection of the spring to both arms, the separation of such arms compels the electrodes to close and keep them forcibly closed while the cam is acting and subsequently closes the arms again and opens the electrodes. I have found in practical use of this device that 40 sparking is regular and reliable without interruptions or failures.

It will be noted that the electrodes have plane flat faces which are brought into contact throughout their meeting areas by a powerful pressure. This pressure and the contact of flat meeting faces breaks and loosens any deposit of carbon and tends to keep such deposits from forming. 45

I do not limit myself to the exact construction and arrangement herein described, and shown in the accompanying drawings, as I 50 desire to avail myself of all modifications and equivalents as fall properly within the spirit of my invention.

Having thus fully described my invention, what I claim as new, and desire to secure by 55 Letters Patent, is—

In an igniter, a stationary electrode, a movable electrode, a rocking arm 14 connected with the movable electrode, an oscillating pin journaled in proximity to said rocking 60 arm, an arm 16 rigidly carried by said pin, a helical spring encircling said pin and having one end connected to the arm 14, means adjustably connecting the other end to said pin, said spring exerting tension on both the 65 arm 14 and the pin, a projection on the arm 16, and a disk rotating with its face in contact with said projection to limit the movement thereof and having a cam projection for rocking the arm 16, substantially 70 described.

In testimony whereof I have affixed my signature, in presence of two witnesses, this 23d day of February, 1905.

HARRY A. JOHNSON.
